United States Patent [19]

Ito et al.

[11] Patent Number: Des. 317,644

[45] Date of Patent: ** Jun. 18, 1991

[54] **COMBINED PRESSURE REGULATOR
FILTER AND LUBRICATOR**

[75] Inventors: **Yasuyuki Ito; Tatsuaki Aoyama, both
of Ichinomiya; Hisanobu Niwa,
Komaki, all of Japan**

[73] Assignee: **CKD Kabushiki Kaisha, Komaki,
Japan**

[**] Term: **14 Years**

[21] Appl. No.: **330,739**

[22] Filed: **Mar. 30, 1989**

[30] **Foreign Application Priority Data**

Sep. 30, 1988 [JP] Japan 63-38442

[57] **CLAIM**

The ornamental design for a combined pressure regulator, filter, and lubricator as shown.

DESCRIPTION

FIG. 1 is a left side elevational view of a combined pressure regulator, filter and lubricator showing my new design;

FIG. 2 is a front elevational view thereof;

FIG. 3 is a right side elevational view thereof;

FIG. 4 is a rear elevational view thereof;

FIG. 5 is a bottom plan view thereof;

FIG. 6 is a top plan view thereof; and

FIG. 7 is a front, top and right side perspective view thereof.

FIG. 1

FIG. 2

FIG. 3

FIG. 4

FIG. 5

FIG. 6

FIG. 7
